United States Patent Office

Des. 183,928
Patented Nov. 18, 1958

183,928

CASING FOR AN INSTRUMENT

Robert H. Hose, Mountainside, N. J., assignor to Minneapolis-Honeywell Regulator Company, Minneapolis, Minn., a corporation of Delaware

Application October 4, 1957, Serial No. 47,977

Term of patent 14 years

(Cl. D26—5)

FIG. 3

Fig. 1 is a front perspective view of a casing for an instrument, showing my new design;

Fig. 2 is a rear perspective view; and

Fig. 3 is a cross-sectional view thereof, taken on line 3—3 in Fig. 1.

I claim:

The ornamental design for a casing for an instrument, substantially as shown.
